FISHING ROD HOLDER

Harold N. Carothers, 4442 Utah Place, Denver, Colo.

Filed May 19, 1960, Ser. No. 60,647

Term of patent 7 years

(Cl. D31—4)

FIG. 3.FIG. 4.

Fig. 1 is a front elevation of a fishing rod holder embodying my new design;

Fig. 2 is a right side elevation thereof, in position for use;

Fig. 3 is a right side elevation similar to Fig. 2, but with the positions of the rod-supporting loops reversed from that of Fig. 2 and the prongs in position for use on a hard surface; and

Fig. 4 is a front elevation, similar to Fig. 1, but with the loops and prongs in folded position for storage.

I claim:

The ornamental design for a fishing rod holder, as shown.
